UNITED STATES PATENT OFFICE

PAUL BUSTARD, OF FREDERICK, OKLAHOMA, ASSIGNOR TO ESKEW H. ARCHER, OF FREDERICK, OKLAHOMA.

CARBURETER.

965,867.

Specification of Letters Patent. Patented Aug. 2, 1910.

Application filed January 11, 1910. Serial No. 537,550.

REISSUED

To all whom it may concern:

Be it known that I, PAUL BUSTARD, a citizen of the United States, residing at Frederick, in the county of Tillman and State of 5 Oklahoma, have invented a new and useful Carbureter, of which the following is a specification.

This invention relates to carbureters of that type in which air is forced through a 10 body of hydro-carbon contained in a vessel which is connected to the engine, the apparatus being designed more particularly for use in connection with internal combustion engines, although not limited to such use.

15 The object of the invention is to provide a carbureter which is so constructed that it will be impossible to flood the engine with gasoline or wet gas, and also to provide a carbureter in which a perfect mixture of air 20 and hydro-carbon vapor is effected, thereby enabling the engine to start on the first complete cycle.

Another object of the invention is to provide a carbureter in which all gas pumps 25 and pipes, as well as needle valves and float feeds are dispensed with, the apparatus being devoid of movable parts to wear out, and get loose or out of order.

The invention also has for its object to 30 provide a carbureter embodying certain novel structural details, resulting in greater efficiency, as will be hereinafter described and claimed.

In the accompanying drawings, forming 35 a part of this specification, Figure 1 is a vertical section of a carbureter constructed in accordance with the present invention. Fig. 2 is a horizontal section on the line 2—2 of Fig. 1.

40 In the drawings, 5 denotes a tank which contains the supply of gasoline or other hydro-carbon, the tank being provided with a filling tube 6 entering through the top thereof, and provided with a suitable closure 7.

45 In the tank is a false bottom 8 to form a water chamber 9, this chamber being located below the false bottom and the supply of gasoline being located in the tank above the said false bottom. The water chamber is

50 provided for the purpose of heating the gasoline to promote vaporization. Warm water is introduced into the chamber through a pipe 10, and it leaves the chamber through a pipe 11, the outlet and inlet ends 55 of said pipes being located respectively ad-

jacent to opposite ends of the chamber, whereby a circulation is maintained therein.

Above the false bottom 8, the tank 5 contains horizontal partitions 12 and 13 respectively, which are spaced from each other, 60 and connected by a circular series of air tubes 14 opening therethrough. One of the ends of the tubes opens into the space between the partition 12 and the false bottom 8, and the other ends of the tubes open into 65 the space above the partition 13.

Located centrally between the partitions 12 and 13 is a perforated tube 15. The diameter of the tube is considerably greater than the diameter of the tubes 14, and the latter extends in a circle around the same adjacent to the tank wall. The partition 12 has perforations 16 which are located in the central part thereof covered by the tube 15. The partition 13 has perforations 17 which 75 extend throughout the entire area thereof, including that portion of the partition which is over the tube 15.

Above the partition 13, the tank 5 contains a partition 18 formed of absorbent material 80 which is held between gratings 19. This partition of absorbent material extends entirely across the interior of the tank, and above the same is located a pair of screens 20 also extending entirely across the interior of the tank.

Above the screens 20, the tank 5 is entered by an air supply tube 21 provided with a valve for controlling the amount of air entering the tank, said valve comprising a 90 sleeve 22 mounted for rotation on the tube 21, and having a slot 23 adapted to register more or less with a slot 24 in the tube.

Below the air tube 21, the tank 5 is encircled on the outside by an air chamber 25, 95 said air chamber being mounted on the tank in any suitable manner, and being annular in form. This chamber is entered by one or more air supply tubes 26 provided with a valve 27 similar to the valve 22 already described. From the air chamber 25, pipes 28 lead into the tank 5, below the partition 12. A plurality of pipes 28 are provided, they extending in a circular series around the tank on the outside thereof. On the top of 100 the tank is mounted an outlet pipe 29 having a laterally directed branch 30 which is connected to the suction pipe 31 of the engine (not shown). The pipe 29 is provided with a relief valve 32 seating on a 105 110

perforated diaphragm 33 located in the pipe 29 above the pipe 30. The upper end of the pipe 29 is closed by a perforated screw cap 34, and between this cap and the valve 32 is 5 interposed a coiled spring 35 for holding said valve seated.

In operation, the tank 5 is filled with gasolene up to within a short distance from the partition 13. On the suction stroke of 10 the engine, air is drawn down the tubes 28 from the chamber 25 into the gasolene, and then passes upwardly through the tubes 14 which are partly immersed in the gasolene. Particles of gasolene are carried upwardly 15 with the air against the partition 18, which thus becomes saturated with gasolene, so that the air passing therethrough is carbureted. The carbureted air passes through the screens 20, and upon meeting the incoming current 20 of air entering the tank through the tube 21 commingles therewith and passes in a perfectly dry state to the engine. The valves 22 and 27 will be set to admit a proper volume of air, and after they are set, the 25 engine may be started any number of times without further adjustment. The air upon entering the body of gasolene below the partition 12, also passes through the perforations 16 into the tube 15, and out of the 30 latter through the perforations thereof into the space between the partition 12 and the partition 13, and thence through the perforations 17 in the latter partition. The air is thus spread through the gasolene, and the 35 latter is carried to all parts of the partition 18. The gasolene does not all go through the partition 18 and the screens 20, a part of it dripping down onto the partition 13, and through the perforations 17 back to the supply. The gasolene is mixed and broken up 40 in going up against the absorbent partition and the screens, and also when dropping back to the tank bottom, so that there is no waste. The perforations 17 are flared in the 45 direction of the partition 18, and their diameter is relatively small at their lower ends, so that the unused gasolene can drip down to the tank bottom, and is prevented from being violently thrown upwardly through 50 the perforations.

A carbureter constructed as herein described, makes it impossible to flood the engine with gasolene or wet gas, and the engine runs cool, and develops a maximum 55 amount of power, using only pure dry gas, which also prevents carbon deposits on the cylinder and cylinder head, and reduces friction to a minimum. The apparatus is also simple in construction, all gasolene 60 pumps, pipes, float feeds and needle valves being dispensed with, and there being no movable parts to get loose or out of order. The efficiency of the apparatus is not affected by water or other impurities in the gaso-

lene, as the partition 18 and the screens 20 65 separate the same.

To the bottom of the tank 5 is connected a pet cock 37 for drawing off the gasolene when it is desired to empty the tank, and also any impurities which may collect in the 70 tank.

The apparatus can be used on any internal combustion engine, and can be made in any form and size.

What is claimed is:

1. A carbureter comprising a tank, spaced partitions in the tank, a perforated tube mounted between the partitions, one of said partitions being perforated throughout its entire area, and the other partition having 75 perforations in its part which is covered by the aforesaid tube, imperforate tubes extending between the partitions and opening therethrough, air supply pipes entering the tank below the partitions, and a partition of 80 absorbent material located above the aforesaid partitions.

2. A carbureter comprising a tank, spaced partitions in the tank, tubes extending between the partitions and opening therethrough, an annular air chamber encircling the tank on the outside thereof, valve-controlled inlets to the chamber, pipes leading from the chamber into the tank below the partitions, and a partition of absorbent material 90 above the aforesaid partitions.

3. A carbureter comprising a tank, spaced partitions in the tank, one of said partitions being perforated, a perforated tube mounted 95 between the partitions, and opening therethrough, and imperforate tubes extending between the partitions and opening therethrough, air supply pipes entering the tank below the partitions, and a partition of absorbent material located above the partitions.

4. A carbureter comprising a tank, spaced partitions in the tank, a perforated tube mounted centrally between the partitions, one of said partitions being perforated 100 throughout its entire area, and the other partition having perforations in its part which is covered by the aforesaid tube, a circular series of imperforate tubes extending 105 between the partitions around the perforated tube, and opening through said partitions, air supply pipes entering the tank below the partitions, and a partition of absorbent material located above the partitions.

In testimony that I claim the foregoing as my own, I have hereto affixed my signature in the presence of two witnesses.

PAUL BUSTARD.
